UNITED STATES PATENT OFFICE

149,100

DESIGN FOR A SOAP CAKE HOLDER

Raymond R. Ward, Brecksville, Ohio

Application August 13, 1946, Serial No. 132,495

Term of patent 14 years

(Cl. D4—3)

To all whom it may concern:

Be it known that I, Raymond R. Ward, a citizen of the United States and a resident of Brecksville, in the county of Cuyahoga and State of Ohio, have invented a new, original, and ornamental Design for a Soap Cake Holder, of which the following is a specification, reference being had to the accompanying drawings, forming a part thereof.

In said drawings:

Fig. 1 is a top plan view of a soap cake holder showing my new design;

Fig. 2 is a side elevational view of the soap cake holder shown in Fig. 1; and

Fig. 3 is a sectional view as taken approximately on the line 3—3, Fig. 1.

In all views, the dominant feature of my design is shown in full lines.

I claim:

The ornamental design for a soap cake holder, substantially as shown and described.

RAYMOND R. WARD.
